UNITED STATES PATENT OFFICE.

FRANK R. WEBER AND CHRISTOPHER J. M. WEBER, OF ST. PAUL, MINNESOTA.

OILING DEVICE FOR JOURNAL-BOXES.

1,344,465.

Specification of Letters Patent. Patented June 22, 1920.

Application filed April 2, 1919. Serial No. 286,887.

To all whom it may concern:

Be it known that we, FRANK R. WEBER and CHRISTOPHER J. M. WEBER, citizens of the United States, residing at St. Paul, in the county of Ramsey and State of Minnesota, have invented certain new and useful Improvements in Oiling Devices for Journal-Boxes, of which the following is a specification.

10 This invention relates to oiling devices to be used in connection with journal boxes for railway car axles.

An object of the invention is to provide in devices of this character, improved oil distributing means that may be easily inserted or withdrawn through the usual end opening of the journal box, and which will require no special modifications in boxes of standard design, preparatory to receiving 20 the invention.

Another object of the invention is to provide in a device of the character described, certain novel features of construction, whereby the oil is economically and efficiently distributed and effectively sealed against invasion of dust and grit.

To this end the invention consists in the features of construction, combination and arrangement of parts hereinafter described 30 and claimed.

Referring to the accompanying drawings: Figure 1, is a vertical sectional view of the entire journal box on a line 1—1 indicated in Fig. 2.

35 Fig. 2, is a vertical sectional view on line 2—2 of Fig. 1.

Fig. 3, is a fragmentary plan view of the floor of the journal box showing part of the invention (partly in section) positioned 40 thereon.

Fig. 4, is a fragmentary vertical section through the floor of the journal box, showing two parts of the invention as they appear in the process of adjusting the device 45 for use and

Figs. 5 and 6 are perspective views of details.

Referring to the drawings, A represents a journal box of ordinary design and comprises a top wall 1, a flat smooth floor 2, and vertical parallel side walls 3. The side walls are interrupted by projecting columns 4, both to accommodate the truss bolts 5 on the outside and the brass 6 on the inside, the lug 55 7 thereof fitting around said column. The rear wall 8 approximately aligns with the

fillet end of the bearing 9 of the axle 10. The end of the bearing is formed with the usual shoulder 11. The brass 6 is provided with the usual Babbitt bearing 12, which, 60 as shown rests on the upper portion of the bearing 9 thereby transmitting the load to the axle. The front end of the journal box is somewhat irregular in shape, having a gradually curved vertical offset 13, in each 65 of the side walls 3 to render the door opening of the box somewhat narrower in width than the main body thereof. The floor 2, rises from said offsets outwardly and upwardly to form a curved inclined portion 14, 70 thereby bringing the base of the door opening a considerable distance above the floor 6. The usual door 15, rotatable on pivot 16 is provided to serve as a closure for the door openings. The descriptive matter in the 75 foregoing applies to one type of ordinary railway car box journal, applicants having elected to show their invention applied to this type.

In Fig. 2, is shown, in cross section the 80 oil reservoir or pan 17, adapted to be slipped through the door opening to the floor 2 and slid under the bearing 9 when the brass is renewed. The pan is rectangular in shape and has two side walls each having an inwardly flaring upper portion 18, the front and rear walls 19 cut away to loosely fit around bearing 9, so that the straight edges 20 of said flaring portions may be brought close to the bearing surface. Removably 85 fitting the interior of the pan is the knock down frame B, one end of which is shown in Fig. 5. The frame rotatably supports a pair of fluted rollers or oil carriers 21, having spindles 22 adapted to roll in the slots 23 in 90 the end members 24 of said frame. The slots are located one on either side of a vertical median line drawn through said end member, and lie in a curve with its center in said line. Said vertical median line also 95 intersects the center of the bearing 9, the radius of the curve of the slots 23 being somewhat greater than the radius of said bearing, the respective centers *a* and *b* thereof (Fig. 2) arranged one above the other. 100 This difference between the two radii, effects a downward and inward movement of the rollers toward each other and toward and against the bearing 9, as is plainly illustrated in Fig. 2. Each end wall is cut away 110 at the top to form the edge 20 of the pan, and is drilled near its lower edge to receive

the pin 25 of the spreader rods 26. The forward lower edge of the pan is formed with an inclined surface 27, adapted to engage the inclined front edge 28 of the flexible 5 thin supporting device C. The thin supporting device C comprises a plurality of comparatively long, narrow slats 29 strung on a continuous wire 30. Each slat, except the first three, is pierced by an opening 31 near 10 each end to receive said wire, the end slat having a long depression to receive the wire in its inclined surface to render the latter non-obstructed. As shown in Fig. 6, the first slats of the supporting device are provided 15 with oblong holes 32, so that when the wire is grasped with the hand by the loop 33 thereof, the two sides of the wire in said three slats will be drawn centerward, thereby withdrawing the latch 34 attached 20 to the wire one at each end of the first of the slats 29. Said first slat is hollow, wherein the latches are adapted to slide, a coil spring 34^a holding said latches in extended position. Thus, when the loop 33 is pulled 25 the latches are first withdrawn and the supporting device then bodily moved. The latches, as shown, are suitably tapered and adapted to engage side edges of the door opening, and be pressed inwardly thereby, 30 and held there until the offset 13 has been passed, when both latches are projected against the wall 3. Thus, when the oil pan has been placed into position under the bearing, the flexible supporting device is 35 next inserted, (Fig. 4) the wedge shape slat initially prying up the pan so that the supporting device may be slid home. The supporting device is of suitable thickness to bring the edge 20 into close proximity to 40 the journal. As the babbitt becomes worn

the axle slowly recedes from the pan, but the oil carriers 21 follow the bearing as they roll toward each other, thereby keeping a constantly flowing supply of oil on the bearing as it is carried in the flutes of the partially submerged rollers from the pan. A lug 35, on the second slat assists in keeping the pan positioned. 45

We claim:

1. In combination with an open front 50 journal box and a journal therein, an oiling device including means rendered effective responsive to the movement of said journal when in contact therewith, a supporting device adapted to be inserted through said open front and under said oiling device to raise the latter to cause it to contact with said journal, said supporting device comprising a plurality of contiguously disposed slats 55 flexibly joined together the forward slat 60 thereof being chamfered to form a wedge.

2. In combination with a journal box having a front opening and an offset in each side wall adjacent said opening and a journal in said journal box, oiling devices under said journal and contacting therewith to be operated thereby when said journal is rotated and a flexible supporting device under said oiling devices to hold the latter in contact with said journal, said supporting 70 device having spring pressed latches to engage said offsets and a handle in connection with said latches for first, when said handle is pulled, withdrawing said latches from said offsets and then withdrawing said supporting device bodily. 75

In testimony whereof we affix our signatures.

FRANK R. WEBER.

CHRISTOPHER J. M. WEBER.
